UNITED STATES PATENT OFFICE.

OSCAR REINHOLD HANSON, OF PEGAU, AUSTRIA-HUNGARY.

HORSESHOE-NAIL-BLANK MACHINE.

SPECIFICATION forming part of Letters Patent No. 579,869, dated March 30, 1897.

Application filed October 12, 1896. Serial No. 608,629. (No model.) Patented in Austria-Hungary December 6, 1892, No. 34,533.

To all whom it may concern:

Be it known that I, OSCAR REINHOLD HANSON, a subject of the King of Sweden and Norway, residing at Pegau, in the Province 5 of Styria, Austria-Hungary, have invented a certain new and useful Improvement in Horseshoe-Nail-Blank Machinery and in the Production of Horseshoe-Nail Blanks, (for which Letters Patent have been obtained, in 10 part, in Austria-Hungary, under date of December 6, 1892, No. 34,533,) of which the following is a specification.

This invention relates to certain improvements in and connected with horseshoe-nail-blank-cutting machinery of a known type and in the production of the blanks, the object being to provide an effective form of horseshoe-nail-blank-cutting machine the purpose of which is to cut the blanks out of 20 a flat ribbon or strip of metal having swollen sides with a very small waste of material.

The apparatus is illustrated in the accompanying drawings, in which—

Figure 1 is a front elevation of the machine. 25 Fig. 2 is a side elevation. Fig. 3 is a plan of the table of the machine, a movable carriage, and connected parts. Fig. 4 is a side and front elevation, respectively, of a part, being a detail of the machine. Fig. 5 is an elevation 30 of the bottom die, showing the metal strip. Fig. 6 is an elevation of the upper cutters and punch with the head in which same are held. Fig. 7 is an under side view of Fig. 6. Fig. 8 is an end elevation of the 35 cutters and holding-head, showing the bottom die and metal strip thereon. Fig. 9 is a side and end elevation, respectively, of the punch. Fig. 10 is a face view and side elevation, respectively, of the cutter for producing a short 40 blank. Fig. 11 is a face view and side elevation, respectively, of the cutter for producing a long blank. Fig. 12 is a section and plan, respectively, on a larger scale, of one form of metal strip having the outlines of some of 45 the blanks marked thereon to illustrate the way in which they are cut. Fig. 13 is a plan, and Fig. 13^a is a side elevation, of a short blank. Fig. 14 is a plan, and Fig. 14^a a side elevation, respectively, of a long blank. Fig. 50 15 is a plan, and Fig. 15^a a side elevation, of the waste piece left in cutting the blanks

illustrated from the strip. Fig. 16 is a plan, and Fig. 16^a is a side elevation, of the finished nail produced from the blank shown in Fig. 13. Fig. 17 is a plan of the waste piece 55 produced in making the finished nail shown in Fig. 16, such waste piece being produced by an operation outside the present invention and being shown only to illustrate the small amount of waste which exists in producing a finished nail from the blank illustrated. Fig. 18 is a similar waste piece produced from the finished nail shown in Fig. 19; and Fig. 19 is a plan, and Fig. 19^a a side elevation, of a finished nail produced from 60 the blank shown in Fig. 14.

A is a casting in the shape of a table; B, a frame secured thereto and carrying upon a shaft C a friction pulley and clutch D, of some convenient form, and having an operating-lever E. An eccentric F is secured upon shaft C and is provided with a handled screw F' to adjust the strap F² of same. This eccentric has a nose F³ on its strap, which acts in a slot in a slide G, which reciprocates between guides H. Such slide G carries the tool-holder Q, in which are held the cutters L L' and a punch L², which operate in connection with a die M carried by the table A. The die M is held in position 70 75 80 tightly by a block N and screws N', Fig. 1.

The metal strip X is introduced into the machine between two vertical rollers O, carried by a bracket O' on a movable carriage P and inserted between the die M and the cutters L L', the cutting being effected by the pressure of the tool-holder carrying the cutters as it is forced down by the nose F³ of the eccentric F.

The carriage P has ears R, on which is pivoted at R² a jaw R', having an extension or arm S, to which is attached four coil-springs T, attached to the upper part of a frame U, secured to the carriage P. The shaft C is provided with a spur-wheel V, which gears with a spur-wheel V' upon a counter-shaft C', which is suitably supported. An eccentric W, also upon shaft C', bears upon a roller W', mounted in the forked end of a rod Y, which is guided by an eye Y', secured to the frame B. A coil-spring Z is attached to an arm Z', secured to the eye Y', and to a spring 90 95 100

- Z^2 , secured to one end of a lever a , pivoted to the frame A at a' . The other end of the lever a carries an arm b , Figs. 1, 2, and 4, pivoted thereto, such arm having a roller b' on a fixed arm thereof and a roller b^2 on an arm which is pivoted to the main arm b at b^3 , as shown. The arm b , with its rollers, passes into a recess formed by a lug c^2 of the carriage P and a lug d of the table A.
- 5 The slide G carries an arm e , bolted to it, said arm carrying at its end in an adjustable fork f a roller f' , which bears upon the arm S of jaw R'. Two coil-springs g , attached to a yoke g' , bolted to the table A at one end 10 and to the lug c^2 of the carriage P at the other, draw the carriage backward when the arm b and its connected parts, which act as a wedge, leave the recess or space between the lug c^2 and lug d .
- 15 The carriage P has a projection h and table A, two projections $h' h^2$, Figs. 1 and 3, with adjusting-screws $l' l^2$, whose purpose is to limit the travel of carriage P. A plate-spring l is fixed to the side of the table A and presses 20 against a rod l^3 , suitably guided, the end l^4 of the rod pressing against the side of the strip X, which is thus forced against the ends of bars $l^5 l^6$, adjustable by bolts l^6 , working in slots thereof, the object of the arrangement 25 being to enable the strip X to be suitably guided and held in position.
- 30 The strip X is held by the jaw R', and at each revolution of shaft C the arm b is raised through lever a , rod Y, roller W', eccentric W, 35 and spur-wheels V V', and rapidly enters the recess or space described and forces the carriage P forward for a limited distance, whereupon the tool-holder Q comes down and two 40 blanks are cut by the cutters, hereinafter described, until the forward movement of the arm S causes roller f' to come in contact with it, thus depressing it and opening the jaw R and raising the slide G with the tool-holder, after which as the arm b retreats from the 45 recess the springs g draw the carriage backward. The arm S, roller f' , arm e , and slide G are raised by the springs T, which when the arm S has moved sufficiently to the left are able to close the jaw R' again upon the 50 strip, which is again forced forward with the carriage.
- 55 A strong compressed-air draft is preferably employed to blow away from the cutters and dies the waste pieces of iron produced in the cutting of the blanks. Such blanks fall through a recess in the dies and under the frame, while the waste pieces are collected in a suitable receptacle.
- 60 The cutters, dies, and punch are shown in Figs. 5 to 11. They consist of a short cutter L, adapted to cut a blank, as in Figs. 13 and 13^a, a cutter L', adapted to cut a long blank, as in Figs. 14 and 14^a, and a compressing-punch L². The three tools are held in the frame Q by a 65 screw m , which passes through a block Q' and abuts against a block n^2 , shaped to the contour

of the side of the cutter L', a shaped block n' being interposed between this and the cutter L and a shaped block n being on the farther side of cutter L, the whole being pressed 70 against a block p , so that they are held firmly in the holder Q. The punch L² is held in the block n' by means of a screw r .

The die M may be of the ordinary construction and has recesses or openings corresponding to the two cutters above. The punch L² is intermediate of the cutters, so that when a short nail-blank is being cut the point of the next or long nail-blank or portion of the bar which is to become a nail-blank is compressed and squeezed by the punch L², and the blank is subsequently produced and separated by the cutter L', the squeezing operation taking place on the swelled portion h' on the strip X, where such portion is used for 85 the point end of the blank, so that the material there is flattened somewhat and is placed more in a condition to be drawn to a long tapered point.

The die M may have a groove t to receive 90 the strip, as shown in Figs. 5 and 8. The knife L, adapted for cutting the short blank, Figs. 13 and 13^a, is shown in Fig. 10. The knife L' (shown in Fig. 11) is adapted to cut the nail shown in Figs. 14 and 14^a. It is provided 95 at the point end with a recess or groove u for the reception of the point of the blank, which, after being slightly flattened by the punch when brought under the cutter, has a thickening at the extreme end, which it is desirable should not be entirely crushed by the pressure of the cutter, such groove also preventing the nail from moving sidewise during the cutting.

The cutters might both be in the shape of 105 the blank shown in Fig. 13 or both in that shown in Fig. 14, according to the shape of the metal strip.

The cutters have a slight inclination on the cutting edge, as shown by the lines $v v'$, 110 Figs. 10 and 11. The punch L² also has a recess u' for the reception of the thickening at the extreme end of the blank, which it produces when it squeezes the swelled portion h to slightly flatten it.

The metal strip X, as shown in Fig. 12, has the swelling h , adapted to form the head of a short nail-blank, and also the point of a longer nail-blank, (in which case it is marked h'), the head of which is formed by the swelling h^2 . These swelled portions may be the same on both sides of the strip or of different shapes, but one swelled portion, even if of the same shape as the other, must be of smaller dimensions on the side which is to form the 125 thickened portion h' for the point.

In Fig. 12 it will be seen that the short blank is cut across the strip from one swelled edge to about the base of the opposite swelled edge to produce a short nail, while the other 130 blank is cut across the full width of the strip. The waste piece of metal between the two

nail-blanks, as shown by the cross-hatching in Fig. 12, is somewhat exaggerated in size, as in Figs. 15 and 15^a, the latter representing the piece as distorted by the stamping of the blanks.

5 By producing a stretched end to the longer nail from the swelled portion *h'* by the process described of flattening such part *h'* prior to cutting the blank a considerable saving of material is effected and a narrower metal strip may be used. Figs. 17 and 18 show the small piece of waste, as stated, which is all that is produced in the subsequent processes of pointing and completing the nails from the blanks.

10 As the strip is fed into the guide-grooves *t* of the die *M* and the tool-holder *Q* moved downward a nail-blank is cut each by cutters *L* and *L'*, the latter cutting a blank with a 15 pressed or squeezed point, which has just been produced by the punch *L²*.

20 What I claim is—

25 1. In a horseshoe-nail-cutting machine, the combination with a supporting-table and supporting-framework attached thereto, of guides attached to said frame, a slide *G* adapted to reciprocate between said guides, means for imparting said motion to said slide, tool-holder *Q* mounted on said slide, cutters *L* and *L'* carried by said holder, blocks shaped to conform 30 to the contour of said cutters carried by said holder for securing the said tools in position, a punch carried between the said cutters, a die carried by the said table below the said 35 cutting-tools, a movable carriage on said table, a pivoted jaw carried by said carriage for holding the material to be cut, adjusting-screws for limiting the travel of said carriage, adjustable guide-bars for holding said material in position, a spring attached to the side 40 of said carriage, a guide-rod abutting against the side of said material under the pressure of said spring for holding in position the said material, a curved arm attached to the said 45 jaw, springs attached to the free end of said arm, a roller adapted to engage the said arm to open the said jaw, an arm attached to the said slide for supporting said roller independ-

50 ent of said carriage, and means for forcing the said carriage forward to feed the material to be cut, substantially as described.

55 2. In a horseshoe-nail-cutting machine, the combination with a movable carriage *P*, a lug *c²* attached to said carriage, the table *A* and a fixed lug *d* carried thereby, springs attached to the table and to the lug of the carriage, an arm *b* and rollers carried at one end of the same, a pivoted lever *a* attached at one end to said arm, a vertical rod *Y* bifurcated at one end and attached to said pivoted lever *a* 60 at the other end, a roller carried in said bifurcation, a spring attached at one end to the said table and at the other to the said rod *Y* near the upper portion thereof, a counter-shaft, an eccentric mounted thereon and 65 adapted to engage the roller carried by the vertical arm *Y*, a gear-wheel mounted on said counter-shaft, a second gear engaging the first, a shaft carrying said second gear and a pulley mounted on the said shaft, substantially as described.

70 3. In a horseshoe-blank-cutting machine, the combination with a tool-holder *Q* consisting of two jaws carrying between the same end holding-blocks *p* and *Q'*, a tightening-screw passing through the block *Q'*, cutters *L* and *L'* carried by said holder, the cutter *L'* having the recess *u* in one end thereof, blocks shaped to conform to the contour of said cutters carried between the aforesaid end blocks 75 and holding the said cutters in position, a punch carried by said holder between the said cutters and having a recess *u'* in the end thereof, a set-screw passing through one of the jaws of said holder and engaging the said 80 punch and a die situated below the said tool-holder, substantially as and for the purposes described.

85 In witness whereof I have hereunto signed my name in the presence of subscribing witnesses.

OSCAR REINHOLD HANSON.
